ADJUSTABLE-INTENSITY ELECTROMAGNETIC AUDIBLE-SIGNAL DEVICE

Arthur B. Poole, Harwinton, Conn.

Application September 27, 1945, Serial No. 618,865

10 Claims. (Cl. 177—7)

1
The present invention relates to improvements in electromagnetic audible-signal devices and relates more particularly to electromagnetic audible-signal devices having means for adjusting the intensity of the signal.

One of the objects of the present invention is to provide a superior audible-signal device of the character referred to, and having a simple construction and arrangement of parts combining low cost for manufacture with reliability of operation.

Another object of the present invention is to provide a superior electromagnetic audible-signal device comprising an electromagnet and an armature, and having a superior construction and arrangement of parts whereby the effective magnetic flux from the electromagnet and acting on the said armature may be conveniently varied without requiring the adjustment of the energy supplied to the said electromagnet.

A further object of the present invention is to provide a superior audible-signal device of the character referred to and comprising a cooperating electromagnet and an armature and having a simple and reliable construction and arrangement of parts whereby the magnetic flux developed by the said electromagnet may be efficiently employed in actuating the said armature gently or violently as may be desired.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in front elevation of one form of audible-signal device constructed in accordance with the present invention;

Fig. 2 is a rear view thereof;

Fig. 3 is a sectional view taken on the line 3—3 of Fig. 1 but on a larger scale;

Fig. 4 is a perspective view of the electromagnet-unit, detached;

Fig. 5 is a similar view of the shell of the electromagnet;

Fig. 6 is a perspective view of the core-unit of the electromagnet;

Fig. 7 is a broken face-view of the mounting-plate;

Fig. 8 is a broken sectional view similar to Fig. 3 but showing another form which the present invention may assume; and

Fig. 9 is a view similar to Fig. 8 but showing still another form which the present invention may assume.

2*The structure of Figs. 1 to 7 inclusive*

An embodiment of the present invention illustrated in the figures referred to, includes an electromagnet comprising a cup-shaped shell 10, a core 11, a spool 12 and an energizing-coil 13.

The shell 10 and core 11 above referred to are formed of soft iron or other suitable magnetic material while the spool 12 is preferably formed of insulating material and upon which the energizing-coil 13 is wound. The spool 12 and its energizing-coil 13 are located within the cup-shaped shell 10 while the core 11 extends axially through the said shell, the spool 12 and the energizing-coil, as is especially well shown in Fig. 3.

The structure of Figs. 1 to 7, inclusive, also includes a mounting-plate 14 preferably formed of non-magnetic but electro-conductive material, an armature 15, an armature-arm 16 to the 20 intermediate portion of which the said armature 15 is rigidly attached, a stud 17 by which the armature-arm 16 is secured at one of its ends to the mounting-plate 14, and a plate-like flux-shunting member 18. The structure also includes 25 a concavo-convex spring-washer 19 and a retaining screw 20.

The shell 10 before referred to includes a substantially-cylindrical lateral wall 21 and an end wall 22 formed integral with the rear end of the 30 said lateral wall and centrally pierced for the accommodation of the rear portion of the core 11 in such manner as to permit the latter to turn, for purposes as will hereinafter appear.

The lateral wall 21 of the shell 10 of the electromagnet is preferably provided with two longitudinal slots 23—23 affording means where any suitable leads from the energizing-coil 13 may emerge for connection to a suitable source of electrical energy.

At its forward end the lateral wall 21 of the shell 10 is provided with two forwardly-projecting pole-salients 24 and 25 located diametrically opposite each other and respectively adapted to project forwardly through arcuate slots 26 and 45 27 extending from front to rear through the mounting-plate 14 as is especially well shown in Fig. 7. The pole-salients 24 and 25 are of sufficient length to project well beyond the front face of the mounting-plate 14 into position to

50 coact with the armature 15 and the flux-shunting member 18 in a manner as will hereinafter appear.

Preferably, and as shown, the mounting-plate 14 is also provided with a slot 28 leading from 55 the outer wall of the arcuate slot 27 to the adjacent edge of the mounting-plate so that the said mounting-plate does not provide an electric circuit around the pole-salient 25 as it does around

the complementary pole-salient 24. In this manner a lag in the flux passing through the pole-salient 24 will occur, while no such lag will occur in the pole-salient 25, thereby serving to provide a more uniform pull upon the armature 15.

The flux-shunting member 18 is formed of soft iron or other suitable material and is riveted or otherwise secured to the core 11 adjacent the forward end thereof. The said member 18 is adapted to be turned edgewise by the said core into and out of registration with the pole-salients 24 and 25 for the purpose of shunting or short-circuiting more or less of the magnetic-flux between the two said pole-salients on the one hand and the core 11 on the other hand.

The flux-shunting member 18 normally has its rear face frictionally-engaged with the forward face of the mounting-plate 14 within the area circumscribed by the inner periphery of the lateral-wall 21 of the shell 10, and is held in such engagement by the tension of the spring-washer 19. The spring-washer 19 has its outer edge resting upon the rear face of the end wall 22 of the shell 10 and has its inner portion seated against the under face of the head of the stud 20 which latter is tightly threaded into the rear end of the core 11 so as to effectively become a part thereof for normal operating purposes.

The forward portion of the core 11 extends through a circular clearance-opening 29 formed in the mounting-plate 14 intermediate the arcuate notches 26 and 27 as is especially well shown in Figs. 3 and 7.

In addition to serving to hold the flux-shunting member 18 in engagement with the forward face of the mounting-plate 14, the spring-washer 19 and the stud 20 also serve to hold the respective forward faces of the shell 10, and the spool 12 against the rear face of the mounting-plate 14.

The energizing-coil 13 may be supplied with alternating current in any suitable manner such for instance as 60 cycle 110 volt current or the said energizing-coil may be supplied with interrupted direct current in any suitable manner such for instance as in the manner common in the art of bells and buzzers.

The energization of the energizing-coil 13 will cause the pole-salients 24 and 25 of the shell 10 to assume one polarity at a given instant while the adjacent end of the core 11 assumes an opposite polarity. The magnetic-flux thus produced will attract the armature 15 against tension of the resilient armature-arm 16, and will cause the striker 30 to strike any suitable object such as a bell or gong. As soon as the current supplied to the energizing-coil 13 is interrupted or reversed the tension of the resilient armature-arm 16 will move the armature 15 away from the pole-salients 24 and 25 and the front end of the core 11 preparatory to the said armature being again attracted.

Should the movement of the armature 15 be not sufficiently violent to meet requirements of audibility, the flux-shunting member 18 may be turned from the full-registering position in which it is shown in Figs. 3 and 4, into a position of partial-registry or completely out-of-registry with the pole-salients 24 and 25. This movement of the flux-shunting member will progressively cause the shunting of less and less of the magnetic-flux and will permit more of the said flux to act directly on the armature 15 to thereby increase the violence of the movement of the

said armature and hence greater audibility of the signal produced.

If desired the striker 30 or its equivalent may be omitted to produce a buzzer-like effect occasioned by the vibration of the armature 15.

The structure of Fig. 8

The structure of Fig. 8 includes the shell 10, spool 12, energizing-coil 13, mounting-plate 14, armature 15, armature-arm 16, stud 17 and striker 30 corresponding to the similar features in the structure of the preceding figures.

In lieu of the movable core 11, the structure of Fig. 8 is provided with a stationary core 31 having an axial-passage 32 extending therethrough. Extending axially through the passage 32 in the core 31 is an adjusting-arbor 33 having rotary movement in the said passage.

Rigidly secured to the forward end of the adjusting-arbor 33, is a clamping-washer 34 serving to rigidly attach a flux-shunting member 35 similar to the flux-shunting member 18 previously described, to the said adjusting-arbor. The clamping-washer 34 as well as the member 35 is preferably formed of soft iron or other suitable magnetic material so as to, in effect, constitute an extension of the forward end of the core 31.

Rigidly mounted upon the projecting rear end of the adjusting-arbor 33, is a knurled finger-piece 36 having its inner end seated against the central portion of a concavo-convex spring-washer 37. The said spring-washer has its outer portion seated against the rear face of the end wall 22 of the shell 10 and has the adjusting-arbor 33 extending through its central portion.

The core 31 is preferably rigid with the end wall 22 of the shell 10 and preferably as shown, its forward end is flush with the forward face of the mounting-plate 14 when the device is assembled as shown in Fig. 8.

The tension of the spring-washer 37 not only serves to frictionally engage the rear face of the flux-shunting member 35 with the forward face of the mounting-plate 14, but also serves to hold the shell 10 and the parts carried thereby in assembled relationship with respect to the mounting-plate 14.

The device of Fig. 8 operates in substantially the same manner as the devices shown in Figs. 1 to 7 inclusive with the exception that the flux-shunting member 35 may be turned with respect to the pole-salients 24 and 25 by means of the adjusting-arbor 33 and the finger-piece 36, without requiring the rotation of the core 31.

The structure of Fig. 9

The structure of Fig. 9 includes the parts and features previously designated by the reference characters 12, 13, 14, 16 to 20 inclusive and 26 to 30 inclusive together with a shell 38 similar to the shell 10 before referred to except that its forwardly-projecting pole-salients 39 and 40 are slightly longer than the pole-salients 24 and 25 of the said shell 10. The shell 38 includes a lateral wall 41 having at its outer end an integral wall 42.

Mounted for rotation within the spool 12 and extending through the end wall 42 is a core 43 generally similar to the core 11 before described and like the same having the retaining-screw 20 threaded into its rear end and passing through the spring-washer 19.

Rigidly secured to the forward portion of the core 43 is the flux-shunting member 18 before described in connection with the embodiment of the invention shown in Figs. 1 to 7 inclusive.

Forwardly of the member 18 the core 43 is formed with a relatively slender neck 44 terminating in a disk-like head 45 formally extending into an aperture 46 formed centrally in an armature 47.

The armature 47 is so sized as to freely fit in the space between the pole-salients 39 and 40 and is secured in rearwardly spaced relationship to the armature-arm 16 by means of studs 48-48.

When the energizing-coil 13 is supplied with current the armature 47 will be pulled inwardly until it substantially aligns with the head 45 of the core 43 to be again released to the tension of the resilient armature-arm 16 when the current supply is interrupted or reversed. The amount of flux which will be caused to flow through the armature 47 may be regulated by the position into which the flux-shunting member 18 is turned in a manner similar to that described in connection with the preceding figures. The rotation of the core 43 will effect the desired turning movement of the flux-shunting member 18 as may be desired.

The particular arrangement of parts whereby the armature 47 or its equivalent fits over the forward end of the core 43 and within the pole-salients 39 and 40 is not per se claimed herein but forms the subject matter of a separate application filed on even date herewith and bearing Serial Number 618,866.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable-intensity electromagnetic audible-signal device, including in combination: a movable signal-armature; an energizing-coil; two complemental magnetic members associated with the said energizing-coil and each having a portion of opposite instantaneous polarity as compared to the other and located adjacent the said signal-armature to pass magnetic flux therethrough; and adjustable flux-shunting means magnetically parallel with and providing a flux-path independent of the flux-path provided by the said armature, the said flux-shunting means being located adjacent the said signal-armature and the respective portions of the said magnetic members and constructed and arranged to adjustably divert magnetic flux between the said portions of the magnetic members and away from the said signal-armature to thus vary the violence of the movement of the latter.

2. An adjustable-intensity electromagnetic audible-signal device, including in combination: a movable signal-armature; an energizing-coil; two complemental magnetic members associated with the said energizing-coil with one thereof extending through the interior of the said energizing-coil and the other thereof extending over the exterior thereof, each of said magnetic members having a portion of opposite instantaneous polarity as compared to the other and located adjacent the said signal-armature to pass magnetic flux therethrough; and adjustable flux-shunting means magnetically parallel with and providing a flux-path independent of the flux-path provided by the said armature, the said flux-shunting means being located adjacent the said signal-armature and the respective portions of 75

the said magnetic members and constructed and arranged to adjustably divert magnetic flux between the said portions of the magnetic members and away from the said signal-armature to thus vary the violence of the movement of the latter.

3. An adjustable-intensity electromagnetic audible-signal device, including in combination: a movable signal-armature; an energizing-coil; a magnetic core extending through the interior of the said energizing-coil and having an end portion adjacent the said signal-armature; a magnetic member extending over the exterior of the said energizing-coil and provided with two pole-salients located adjacent one end of the said core and adjacent the said signal-armature to cause the latter to carry flux between the two said pole-salients and the said core; and adjustable flux-shunting means magnetically parallel with and providing a flux-path independent of the flux-path provided by the said armature, the said flux-shunting means being located adjacent the said signal-armature, the pole-salients of the said member and the adjacent end of the said core and constructed and arranged to adjustably divert magnetic flux between the said pole-salients and the said core and away from the said signal-armature to thus vary the violence of the movement of the latter.

4. An adjustable-intensity electromagnetic audible-signal device, including in combination: a movable signal-armature; an energizing-coil; two complemental magnetic members associated with the said energizing-coil with one thereof extending through the interior of the said energizing-coil and the other thereof extending over the exterior thereof, each of said magnetic members having a portion of opposite instantaneous polarity as compared to the other and located adjacent the said signal-armature to pass magnetic flux therethrough; and an adjustable flux-shunting member mounted for turning movement about an axis substantially coaxial with the said energizing-coil and magnetically parallel with and providing a flux-path independent of the flux-path provided by the said armature, the said flux-shunting means being located adjacent the said signal-armature and the respective portions of the said magnetic members, the said flux-shunting member being constructed and arranged to adjustably divert magnetic flux between the said portions of the magnetic members and away from the said signal-armature to thus vary the violence of the movement of the latter.

5. An adjustable-intensity electromagnetic audible-signal device, including in combination: a movable signal-armature; an energizing-coil; a magnetic core extending through the interior of the said energizing-coil and having an end portion adjacent the said signal-armature; a magnetic member extending over the exterior of the said energizing-coil and provided with two pole-salients located adjacent one end of the said core and adjacent the said signal-armature to cause the latter to carry flux between the two said pole-salients and the said core; and an adjustable flux-shunting member magnetically parallel with and providing a flux-path independent of the flux-path provided by the said armature, the said flux-shunting means being mounted for turning movement about an axis substantially coaxial with the said energizing-coil and the said core and located adjacent the said signal-armature, the pole-salients of the said member and the adjacent end portion of the said core, the said flux-shunting

member being constructed and arranged to adjustably divert magnetic flux between the said pole-salients and the said core and away from the said signal-armature to thus vary the violence of the movement of the latter.

6. An adjustable-intensity electromagnetic audible-signal device, including in combination: a movable signal-armature; an energizing-coil; a rotatable magnetic core extending through the interior of the said energizing-coil and having an end portion adjacent the said signal-armature; a magnetic member extending over the exterior of the said energizing-coil and having a portion located adjacent the said signal-armature to cause the latter to carry flux between itself and the said core; an adjustable flux-shunting member located adjacent the said signal-armature and the respective portions of the said core and magnetic member to adjustably divert magnetic flux between the said magnetic member and the said core and away from the said signal-armature, the said flux-shunting member being secured to the end portion of the said core adjacent the said signal-armature for turning movement with the said rotatable core.

7. An adjustable-intensity electromagnetic audible-signal device, including in combination: a movable signal-armature; an energizing-coil; a rotatable magnetic core extending through the interior of the said energizing-coil and having an end portion adjacent the said signal-armature; a magnetic member extending over the exterior of the said energizing-coil and provided with two pole-salients located adjacent one end of the said core and adjacent the said signal-armature to cause the latter to carry flux between the two said pole-salients and the said core; and an adjustable flux-shunting member located adjacent the said signal-armature, the pole-salients of the said member and the adjacent end of the said core and constructed and arranged to adjustably divert magnetic flux between the said pole-salients and the said core and away from the said signal-armature, the said flux-shunting member being carried by and turnable with the said rotatable core.

8. An adjustable-intensity electromagnetic audible-signal device, including in combination: a movable signal-armature; an energizing-coil; two complementary magnetic members associated with the said energizing-coil with one thereof extending through the interior of the said energizing-coil and the other thereof extending over the exterior thereof, each of said magnetic members having a portion of opposite instantaneous polarity as compared to the other and located adjacent the said signal-armature to pass magnetic flux therethrough; an adjustable flux-shunting member magnetically parallel with and providing a flux-path independent of the flux-path provided by the said armature, the said flux-shunting means being located adjacent the said signal-armature and the respective portions of the said magnetic members and constructed and arranged to adjustably divert magnetic flux between the said portions of the magnetic members and away from the said signal-armature; and rotary adjusting-means also extending through the interior of the said energizing-coil and coupled to the said flux-shunting member to adjust same.

9. An adjustable-intensity electromagnetic audible-signal device, including in combination: a mounting-plate provided with a clearance-opening and with two salient-receiving openings respectively on either side of the said clearance-

opening; a magnetic shell located to the rear of the said mounting-plate and provided with two pole-salients respectively projecting forwardly through the salient-receiving openings in the said mounting-plate; an energizing-coil within the said magnetic shell; a magnetic core extending through the interior of the said energizing-coil and having an end projecting forwardly through the clearance-opening in the said mounting-plate; a movable signal-armature located forwardly of the said mounting-plate and cooperating with the pole-salients and the said shell and the adjacent end of the said core; an adjustable flux-shunting member mounted for turning movement about an axis substantially parallel with the axis of the said energizing-coil and located forwardly of the said mounting-plate and rearwardly of the said signal-armature, the said member being magnetically associated with the pole-salients of the said shell and with the adjacent portion of the said core to shunt magnetic flux therebetween; and means for turning the said flux-shunting member.

10. An adjustable-intensity electromagnetic audible-signal device, including in combination: a mounting-plate provided with a clearance-opening and with two salient-receiving openings respectively on either side of the said clearance-opening, the said mounting-plate also being formed with a passage leading from one of the said salient-receiving openings to an edge of the mounting-plate to avoid the circulation of eddy-currents in the portion of the mounting-plate around the particular one of the hereinafter-mentioned pole-salients which extends through the salient-receiving opening from which the said passage leads; a magnetic shell located to the rear of the said mounting-plate and provided with two pole-salients respectively projecting forwardly through the salient-receiving openings in the said mounting-plate; an energizing-coil within the said magnetic shell; a magnetic core extending through the interior of the said energizing-coil and having an end projecting forwardly through the clearance-opening in the said mounting-plate; a movable signal-armature located forwardly of the said mounting-plate and cooperating with the pole-salients and the said shell and the adjacent end of the said core; an adjustable flux-shunting member mounted for turning movement about an axis substantially parallel with the axis of the said energizing-coil and located forwardly of the said mounting-plate and rearwardly of the said signal-armature, the said member being magnetically associated with the pole-salients of the said shell and with the adjacent portion of the said core to shunt magnetic flux therebetween; and means for turning the said flux-shunting member.
